UNITED STATES PATENT OFFICE.

FRANCIS J. GREEN, OF DETROIT, MICHIGAN, ASSIGNOR TO THE AMERICAN ENGINEERING COMPANY, OF DETROIT, MICHIGAN, A CORPORATION OF SOUTH DAKOTA.

WIRELESS TELEGRAPHY.

SPECIFICATION forming part of Letters Patent No. 758,006, dated April 19, 1904.

Application filed January 9, 1903. Serial No. 138,343. (No model.)

To all whom it may concern:

Be it known that I, FRANCIS J. GREEN, a citizen of the United States, residing at Detroit, county of Wayne, State of Michigan, have invented a certain new and useful Improvement in Wireless Telegraphy, of which the following is a specification, reference being had to the accompanying drawings, which form a part of this specification.

10 My invention has for its object certain new and useful improvements in wireless telegraphy and in signaling apparatus employed in connection therewith.

My present invention in some of its features is especially adapted for transmitting and receiving signals upon vessels and upon railway-trains. While other features of my present invention are of wider scope and are adapted for various uses, I show the same herewith, 20 as applied to vessels for marine signaling and also to the cab of a locomotive for railway signaling.

In all present systems of danger-signals upon railways reliance is had upon track or 25 road connections with semaphore or other signals placed alongside the track. I propose to do away entirely with all outside connections and place on each locomotive a signaling apparatus, utilizing Hertzian waves as a means of 30 communication. In this manner the signal is given directly in the cab of the locomotive and under the engineer's immediate notice, so no matter how thick the weather may be the signal is in no way obscured.

35 While I do not limit myself to any particular use to which my invention may be put, when applied to vessels it is designed that each vessel shall be equipped both with the transmitting mechanism and with a plurality 40 of receiving mechanisms embodied in my invention. So, also, when applied to railway-trains each train is designed to be equipped with the transmitting mechanism and with a plurality of receiving mechanisms.

45 The objects of my invention include apparatus for giving and receiving signals, the apparatus at the same time denoting the direction from which any given signal is received. My apparatus is also adapted to receive sig-

nals at a given station or location from more than one direction at the same time.

Certain principles of my invention, as well as certain features of the present apparatus, may be used for the wireless transmission and reception of messages, as well as for signaling 55 purposes.

The system of wireless transmission of electric waves or impulses as applied to danger-signals and for railways consists, essentially, of a transmitter and receivers of suitable form 60 placed on each locomotive-cab on the road or upon each vessel.

My invention contemplates suitable devices, automatic in their working, whereby no train can approach another within a given radius 65 from any direction, either in front or behind, without each engineer being warned of the approach of another train and the direction the approaching train is going, as well as whether it is in front or behind him.

70 In other systems of transmitting electrical impulses or Hertzian waves through the air dependence has heretofore been placed upon the Morse key system to effect the transmission of the signals or upon other analogous 75 instruments. By my invention, however, means are provided for making the transmission of the signals automatic.

Certain principles and features embodied herein are also designed and adapted for transmitting and receiving signals or messages simultaneously at the same station or location.

80 My invention contemplates means for holding or delaying the action of the receiving-circuit in order to give the local circuits time 85 in which to perform their functions properly; also, for still further delaying the decoherer of the coherer or receiver by delaying the action of the tapper; to provide a tapper to effect the decoherence of the coherer adapted to give a 90 single short tap; to provide an improved circuit-breaker adapted to give varying signals; to provide a signal whereby the operator can see when the transmitting mechanism is working properly; to further provide a special annunciator to indicate the direction from which a given signal is received.

95 My invention therefore consists of these and

other features of general construction, as well as the combination and arrangement of devices hereinafter described and claimed, and illustrated in the accompanying drawings, in 5 which—

Figure 1 is a view in perspective, illustrating features of my invention. Fig. 2 is a diagrammatic view illustrating features of the receiving mechanism embodied in my invention, 10 the same being more particularly adapted in certain of its features for application to vessels. Fig. 3 is a general diagrammatic view of the receiving-circuits embodying features of my invention more particularly adapted for 15 use in railway signaling. Fig. 4 shows the connections for the special annunciator when applied to railway signaling. Fig. 5 is a diagrammatic view showing features of my improved transmitting mechanism. Fig. 6 is a 20 detail view showing one face of the signal-box for the circuit-breaker of the transmitter. Fig. 7 is an exterior view, in side elevation, of the special annunciator employed in marine signaling. Fig. 8 is an exterior view of the 25 annunciator illustrated in Fig. 3, designed for railway signaling. Fig. 9 is a view in side elevation and vertical section showing the transmitting and receiving mechanisms for the railway signaling. Fig. 10 is a diagrammatic 30 view illustrating the general principles by which the differentiation of the signals is accomplished. Fig. 11 is a diagrammatic view illustrating a modification in the arrangement of the compartments in which the plurality of 35 receivers are located.

In carrying out my invention the transmitting and receiving mechanisms are mounted upon any suitable support, the transmitting mechanism being preferably located above the 40 receiving mechanism and segregated therefrom by means of a wire netting or gauze. While a solid-metal plate may be used to prevent the passage of electric waves through the air or to secure the segregation of the transmitting mechanism, I have found that wire netting or gauze serves the same purpose at a much less expense, and therefore in insulating the various parts of this machine from the effect of the electric waves I prefer to universally adopt the use of the wire netting or 45 gauze, although I do not limit myself solely thereto, as in all places where the wire netting or gauze is shown or described a metal plate of any desired thickness might be substituted therefor and the action remain the same.

In the drawings, *a* represents any suitable support for my improved transmitting and receiving mechanisms. In Fig. 1 the support is more particularly adapted for use where 50 my invention is applied to vessels. In Fig. 9 the support shown is more particularly designed for use where my invention is employed for railway signaling. I do not limit myself to any particular construction or form 55 of the support in which the connections and

mechanisms may be inclosed or upon which they may be located.

My invention contemplates the employment of a plurality of receiving mechanisms, four receiving mechanisms being shown in Fig. 2. 70 The different receiving mechanisms are segregated the one from the other by suitable walls or partitions, preferably of wire netting or gauze. In Fig. 3 of the drawings two receiving mechanisms are indicated at *b* and *c*. 75 In Fig. 2 additional receiving mechanisms are indicated at *d* and *e*. The separate features of construction of said receiving mechanisms will be hereinafter more fully described. In order to differentiate the signals received by 80 the plural receiving mechanisms, said mechanisms are separated and shielded the one from the other by suitable dividing-walls, (indicated at *f*,) preferably composed of wire netting or gauze, said walls forming compartments opening only in the direction from which it is desired to receive signals by the particular receiving mechanism thus protected. In Fig. 85 3 two such compartments are shown, (indicated at *g* and *h*,) said compartments being 90 arranged so as to receive signals from opposite directions by corresponding receiving mechanisms. In Fig. 2 four such compartments are indicated at *g*, *h*, *i*, and *j*, each shielded 95 by walls, *f*, one from the other. The application 100 of this principle of differentiating the signals one from another as applied, for example, upon vessels will be more clearly understood by reference to the diagrammatic view Fig. 10, said view being introduced simply to illustrate 105 this principle of the differentiation of the direction from which any given signal is received. In said Fig. 10 *k* may denote a vessel upon which my improved apparatus is placed, and the numerals 1, 2, 3, and 4 denote the 110 different wings of the dividing-wall. It will be readily apparent that if said wings were extended they would be carried out on the radial lines indicated by the longer dotted lines. Theoretically a metal plate intercepting a 115 Hertzian wave will cast a sharp definite electrical shadow behind it; but in practice I find that instead of the edges of this electrical shadow being sharply defined there is a certain amount of diffusion. For example, theoretically, Hertzian waves transmitted from any point between two adjacent radial lines, as between the lines 5 6, 6 7, 7 8, and 8 5, would affect the receiver in the corresponding compartment 1, 2, 3, or 4 only; but in practice 120 it is found that owing to the diffusion above mentioned there is certain space adjacent to each of the radial lines 5, 6, 7, and 8 within which the electrically-transmitted waves will affect two adjacent receivers in two 125 adjacent compartments. Such spaces are indicated by the shorter dotted radial lines 9, 10, 11, 12, 13, 14, 15, and 16. It will be obvious that Hertzian waves originating at any point between the lines 10 11, 12 13, 14 15, 16 9 130

would simultaneously affect the corresponding receivers 1, 2, 3, and 4 only, while any Hertzian wave originating at any point between the lines 11 12 would simultaneously affect the two receivers in compartments 2 and 3. 5 Also waves originating at any point between lines 15 and 16 would simultaneously affect the receivers in compartments 3 and 4, while waves originating at any point between the lines 9 and 10 would simultaneously affect the receivers in the compartments 4 and 1. It is 10 obvious that as applied to a vessel the receiver in compartment 1 opens to the front or bow of the vessel, that in the compartment 2 to the starboard beam, that in the compartment 3 toward the stern, and that in the compartment 4 toward the port beam. If another vessel carrying the apparatus embodied in my 15 invention was located between the lines 10 and 11 and was to send a signal, the receiver in the compartment 1 of a corresponding vessel would be actuated. The receiver in each compartment is connected, as will hereinafter be described, with an annunciator, which, as 20 illustrated in Fig. 7, for example, may be provided with four lights, (indicated at *l*, *m*, *n*, and *o*.) These lights serve to indicate the direction from which the signal is received, the lights being actuated by the corresponding receivers. 25 Thus a signal received from a vessel between the lines 10 and 11 might be indicated by the flashing of the light *l*. A signal received between the lines 12 and 13 would be indicated by the flashing of the light *m*. A signal received between the lines 14 and 15 would be indicated by the flashing of the light *n*, while a signal received between the lines 16 and 9 would be indicated by the flashing of the light *o*. So, also, it will be obvious that signals received between the lines 11 and 12 would be indicated by the flashing of both lights *l* and *m* simultaneously. Signals received between the lines 13 and 14 would be indicated by the simultaneous flashing of both lights *n* and *o*. 35 So, also, signals received between the lines 9 and 10 would be indicated by the simultaneous flashing of both lights *o* and *l*. In this manner the location of any vessel transmitting the signals either from ahead, from the 40 starboard bow, the starboard beam, the starboard quarter, the stern, the port quarter, port beam, or port bow can be readily ascertained by the flashing of the corresponding light or lights, as hereinabove stated. 45 It will be understood that the receiving mechanisms all correspond in their construction and arrangement, so that the description of one receiving mechanism will serve for a full understanding of the construction and arrangement of each of the receiving mechanisms. I do not limit myself to any precise number of receiving mechanisms which may be employed. Should it be desired to still 50 more sharply define the location of a vessel transmitting signals, a still larger number of

receiving mechanisms might be employed, each receiving mechanism being segregated from the others in a manner similar to that already described by intervening walls or wings placed at proper angles. I would have 70 it understood that I do not limit myself to any particular construction or arrangement of said metal walls and the wings with which said walls are provided, a plurality of receiving mechanisms of any desired number being 75 contemplated within the scope of my invention, each segregated from other receivers and the transmitting mechanism. As illustrated in Fig. 11, the various compartments *g*, *h*, *i*, and *j* might be entirely separated one 80 from another and located at points distant one from another, but each opening outward in a manner similar to that already described, the receiver in each compartment being connected with a common annunciator, the annunciator being located wherever it might be most convenient—as, for instance, on the bridge of the vessel. 85 I will now proceed to describe one of the receiving mechanisms, the description being 90 applicable to each of the receiving mechanisms which may be employed. A coherer of the usual form is indicated at *p* in circuit with a relay *q* and a battery *r*. The tongue *s* of the relay is arranged so that 95 when the relay is closed by the action of the coherer it will form two separate contacts with contact-points, (indicated at *t* and *u*.) the contact-point *t* being in circuit with a retarding-coil *v*, which is wound in the shape of a hollow solenoid, the solenoid being in circuit with an additional battery *w*, said battery being electrically connected with the opposite end of the relay-tongues, as indicated at *x*. It will thus be evident that when the relay-tongue is 100 in contact with the point *t* the circuit is completed through the tongue, the contact *t* thereby actuating the solenoid *v*. Within the solenoid *v* is a bar or core of soft iron (indicated at *y*) and connected through a battery *z* to a 105 hollow tapping-solenoid 17. The solenoid *v* being actuated the core *y* is drawn up within it and comes in contact with a contact-plate 18 in electrical circuit with the tapping-solenoid 17. The contact being made between the core 110 *y* and the plate 18 the tapping-circuit is closed. The tapping-solenoid is provided with a tapping-core 19, similar to the core *y*. When the tapping-solenoid 17 is actuated, the tapping-core 19 is operated, striking the coherer 115 to decohere the same. Immediately upon this decoherence being effected the circuit through the coherer is broken, and the relay-tongue *s* is drawn back by means of a spring 20, thus opening all of the circuits already described, 120 as well as the signal-circuit. The signal-circuit is operated through the same relay-tongue *s*, closing with the contact *u*, a circuit through an additional battery 21 actuating the lights *l m n o*, as the case may be, forming a part of 125 130

an annunciator (shown more particularly in Fig. 7) in the signaling-circuit with the last-mentioned battery, the battery 21 being electrically connected back to the relay-tongues, 5 as shown. In addition to the signaling-light in the signaling-circuit an additional signal may be provided in the same circuit—as, for instance, a bell, (indicated at 22.)

In Figs. 3, 4, 8, and 9 is shown a slight modification in the annunciator in the signaling-circuit. The connection of the signaling-circuits are the same as those heretofore described, the annunciator device being somewhat different from that illustrated in Fig. 2, for example. 10 Where signals are only to be received from two opposite directions, as in railway signaling, the signaling-lights *l m n o* are replaced in the signaling-circuit by lights in the annunciator, which show when no signal is being received from either direction, and if at any time a signal should be received it will be shown at once by the changing of one or both of the lights aforesaid into those of another color. In this modified form of an annunciator I provide electromagnets 23 and 24 and a battery 25, in circuit of which battery are two lights 26 and 27, which may preferably be white lights, said lights being in circuit through contacts at 28 and 29 with corresponding armatures 30 and 31 of the electromagnets 23 and 24. Said armatures are constructed, preferably, in the form of bell-cranks. When said magnets are actuated, the corresponding armatures are drawn down, 15 causing the contacts at 28 and 29 to be broken, the adjacent end of the armature forming new contacts, as at 32 and 33, thus extinguishing the white lights 26 and 27 and operating additional lights 34 and 35, which may be colored to denote front and rear, said lights 34 and 35 being fed from the same battery as those by which the white lights aforesaid are supplied. The light 34, for example, might be a red light and the light 35 a green light. 20 Thus when no signal is being received from either direction the white lights to indicate the front and rear are in operation, showing that the track is clear. Should a signal be received from the front, the white light 26 is extinguished and the red light is thrown into circuit. Likewise should no signal be received from the rear the white light 27 is in circuit; but should a signal be received from the rear the light 27 is cut out and the green light 35 is thrown into circuit. 25

The transmitting mechanism is more particularly shown in Figs. 5, 6, and 9, and consists, essentially, of an induction-coil 36, operated by a battery 37 in circuit therewith, a 30 circuit-breaker being interposed in said circuit, the circuit-breaker being of such construction as to automatically send any desired combination of Hertzian waves at regular intervals. The circuit-breaker is shown operated by a motor, (indicated at 38,) and consists

of a rotatable shaft 39, provided with disks 40 and 41, mounted thereupon and rotatable therewith, said disk 40 having on its periphery a suitable toothed portion or projection 42, while the disk 41 is shown provided with three 70 projections, (indicated at 43.) Adjacent to said disks are tilting arms or levers 44 and 45, arranged upon an axis 46, one end of each of said arms being in the primary circuit of the induction-coil 36. Contact-plates 47 and 48 75 are provided to form contact with the adjacent ends of the arms 44 and 45, a switch 49 being provided whereby either of the plates 47 and 48 may be turned into circuit by moving the switch to the corresponding contacts 80 50 and 51. The arms 44 45 are also provided with contact-points 52 and 53, which when said arms are tilted form contact with the corresponding plates 47 and 48. The arms 44 and 45 are actuated by the rotation of the adjacent disks 40 and 41. Thus, for example, when the projection 42 of the disk 40 strikes the adjacent end of the arm 44 said arm is tilted and a contact is formed with the corresponding plate 47. So, also, when one of the 90 projections 43 strikes the adjacent end of the arm 45 said arm is tilted, forming contact with the plate 48. Obviously the arm 45 will be tilted three times, making and breaking corresponding contacts with the plate 48. It 95 will be evident that if it be desired to throw either one of the combinations of signals into circuit by the rotation of the disks 40 and 41 it can be done by correspondingly adjusting the switch 49. In this manner, for example, the operation of the arm 44 by the disk 40 might be understood to signify that the train sending forth the signal is going in a certain direction, while the combination of signals made by the rotation of the disk 41 might be 100 understood to indicate that the train was traveling in the opposite direction. Upon the closing of these contacts 52 and 53 the circuit is closed through the primary winding of the induction-coil, thus causing an induced current in the secondary winding and the passage of a spark between the terminals 54 and 55. At every passage of this spark between the terminals a Hertzian wave is sent forth in all 105 directions, and any receiver within a given 110 distance of the transmitter is affected by waves emitted from the transmitter and will indicate the direction from which this wave is received in the manner heretofore described. The light 56 is in parallel across the terminals of the 115 primary induction-coil and operates at every 120 contact formed by the circuit-breaker. This light is to show that the circuit-breaker is operated each time the contact is closed, the circuit being thus closed through the light, and thereby 125 flashing it. By this means the engineer on a locomotive can tell whether the transmitting apparatus is properly working. The entire transmitting mechanism must, with the exception of the terminals and the lights, 130

be inclosed within a covering of wire netting or gauze, as shown.

In Fig. 6 is shown a front elevation of the signal-box 57, in which is inclosed the motor 38 and the circuit-breaking mechanism. In Fig. 9 the mechanism is shown attached to the cab 58 of the locomotive, the induction-coil and its terminals, together with the receivers, being preferably located on the top of the cab, the circuit-breaker, motor, and signal-box, being located under the top of the cab. The various batteries, relays, and retarding-coils may be located under the engineer's seat, (indicated at 59,) the annunciating mechanism being located most conveniently in front of the engineer as he occupies his accustomed seat.

I have shown the transmitting mechanism actuated by the motor 38, but I would have it understood that the transmitting mechanism might be operated in any suitable manner or by any suitable means, as by clockwork, for example. It will be understood that if a motor 38 be employed it may be connected with any suitable source of electrical supply.

The operation of the various features of my invention will now readily be understood and is as follows: For transmitting signals either upon a vessel, a locomotive, or otherwise, where signals alone are desired to be used, the transmitting mechanism is designed to be in constant and automatic operation, giving out continuously a definite series of Hertzian waves, the particular kind of signals being governed by the circuit-breaking mechanism. I do not, however, limit myself to any specific circuit-breaking mechanism, my invention including within its scope any suitable mechanism for causing a desired system of signals. My invention contemplates a different series of signals to be given out by the transmitting mechanism under the control of the operator, so that one system of signals may be caused, for example, by a transmitter carried by a locomotive running in one direction, while a different system of signals may be caused by the transmitting mechanism upon a locomotive running in the opposite direction, these systems being under the control of the engineer through the switch 49. In this matter the rules of the road might direct one particular system of signals to be employed upon a locomotive running northward, for example, and another system of signals to be employed upon locomotives running southward, so that when the signals are received by the receiving mechanism of another engine the engineer can readily tell in which direction the corresponding engine is running. Supposing an engineer to be leaving the yard to go in a certain direction, he adjusts his switch 49 accordingly and he pays no further attention to the transmitting mechanism, as he is constantly kept informed that his mechanism is operating by means of the white light 56 flashing at regular inter-

vals. If, for instance, his trip is northward, he would move the switch 49 to the contact-point 50. This being done, it would throw into operation the disk 40, thereby closing the contact 53 at regular intervals. At each closing of the contact 53 the circuit is closed through the primary of the induction-coil at regular intervals, thereby causing a single spark to pass between the secondary terminals 54 and 55 of the induction-coil 36. At each passage of this spark a Hertzian wave is formed, which from its character travels in all directions from the point of origination. Also at each closing of the contact 53 the circuit is closed in which is located the light 56, thereby flashing the light at every spark passed between the terminals and constantly notifying the engineer that his transmitting apparatus is working properly. If now while running in this northward direction he should approach another train in front of him and going in the same direction, the corresponding receiver of the other engine—for instance, the receiver designated at *b*, Fig. 9—would be affected. Upon the reception of the wave at this receiver the circuit is closed through the corresponding coherer *p*, which in turn actuates the corresponding relay *q*, drawing over the relay-tongue *s* and closing the contact through the retarding-circuit and the signal-circuit. The retarding-circuit being closed, the core *y* is drawn within the corresponding solenoid and coming into contact with the contact-plate 18 the tapping-solenoid is actuated. Immediately upon this tapping-solenoid being actuated the tapping-core 19 is drawn within it, thereby striking the coherer, and decohering it breaks the circuit, and the relay-tongue flies back to its original position. While contact may be made direct with the tapping-solenoid by means of the relay-tongue, it is found in so doing the decoherence of the coherer is effected too rapidly and the signaling-circuit is not given time to properly perform its functions. In order to appreciably lengthen the time of contact, the retarding-coil *v*, as above, is introduced, which by means of its peculiar action takes an appreciable length of time to operate, and so delays the closing of the tapping-circuit, thus giving time for a full and perfect contact in the signaling-circuit. At the same time that the relay-tongue *s* is operating the retarding and tapping circuits it makes a contact through *u* with the signaling-circuit, in which circuit is situated the annunciator and the alarm-bell. The annunciator is so arranged that upon the face of it there are two divisions, front and rear. In each of these divisions is a white light, which burns constantly as long as no signal is being received. The contact through which this white light is operated is at 28, which contact is closed by means of the rocking armature 30. Immediately upon the signaling-circuit being actuated the electromagnet 23 draws over the armature 130

30 and opens the contact 28, thereby cutting out the white light and closing the contact 32, throwing the red light 37 into circuit. By this means as long as no signal is being received either from the front or rear the engineer is so informed by the white lights in the annunciator. Immediately, however, upon a signal being received from an approaching locomotive the corresponding front or rear light is extinguished and the red or green light is thrown into circuit, as the case may be. It is understood that in constructing this apparatus the transmitting mechanism and connections should be carefully segregated by inclosing them in appropriate envelops, as by means of wire netting or gauze, for example, as already described, with the exception of the light 56 and the transmitting-terminals 54 and 55, which should be free and capable of transmitting waves in all directions. Also all parts of the receiving mechanism and connections should be similarly inclosed, with the exception of the coherers, which should be open or exposed in the direction from which it is desired to receive a signal. Similar results, it will be understood, would be attained where vessels are thus equipped. Within the scope of my invention also receivers may be located at all cross-roads and railway-stations to indicate to the station or to passers-by the approach of the trains, said receivers at such locations being provided with any suitable danger-signals actuated thereby. Within the scope of my invention also transmitters may be located in the caboose of freight-trains, for example, whereby the engineer of the train would at once be notified if his train should break in two.

While I have shown in Fig. 1, for example, certain relations of the mechanisms, I would have it understood that I do not limit myself to any particular relations of the various elements embodied in my invention. The assemblage of mechanisms illustrated in Fig. 1 will be a convenient arrangement for the application of my invention to vessels; but I do not limit myself thereto, the said figure being introduced more particularly to show the method of segregating the transmitting from the receiving mechanisms and the receiving mechanisms one from the other.

From the foregoing description it will be understood that the direction in which another train may be is indicated by the color of the light, and the direction in which it is moving, whether north or south, is indicated by the character of the intervals of the flashing of the lights or the ringing of the bells. For instance, one ring and one flash of the light at regular intervals might be made to mean that the train was moving northward, and three rings, with the corresponding three flashes of the light, would mean that the train was moving southward. In this way the engineer can tell both whether the train is in

front or behind him from the color of his lights and whether it is moving in the same direction as he is or in opposite direction from the intervals at which the light flashes and the bell rings.

The circuit through the coherer operating the relay may be called the "receiving-circuit." The circuit operated by the relay may be called the "relay-circuit." The circuit operated by the relay in which the lights are located may be called a "signal-circuit." The circuit operated by the relay in which the retarding-coil is situated may be called the "retarding-circuit," and the circuit operated by the retarding-coil in which the tapper is located may be called the "tapping-circuit."

What I claim as my invention is—

1. The combination with a Hertzian-wave receiver, of an electrical circuit through said receiver, a relay actuated by the circuit through the receiver, a signal-circuit actuated by the relay-circuit, and variable signal-lights in the same signal-circuit.

2. The combination with a Hertzian-wave receiver, of an electrical circuit through said receiver, a relay-circuit actuated by the circuit through the receiver, a signal-circuit actuated by the relay-circuit, and differing signal-lights in the signal-circuit to indicate the direction from which an electrical impulse may be received.

3. A Hertzian-wave-receiving apparatus comprising a receiving-circuit, a relay-circuit, a signal-circuit containing variable signals, a retarding-circuit, and a tapping-circuit.

4. A Hertzian-wave-receiving apparatus comprising a plurality of receiving-circuits, a plurality of relay-circuits, a single signal-circuit, and plural signals in the signal-circuit.

5. A Hertzian-wave-receiving apparatus comprising a plurality of receiving-circuits, a plurality of relay-circuits, and a single signal-circuit, said single signal-circuit actuated by any one of the relay-circuits.

6. A Hertzian-wave-receiving apparatus comprising plural receiving-circuits, plural relay-circuits, a single signal-circuit actuated by any one of the relay-circuits, and variable signals in the signal-circuit.

7. A Hertzian-wave-receiving apparatus comprising plural receiving-circuits, plural relay-circuits, plural retarding-circuits, plural tapping-circuits, and a single signal-circuit.

8. The combination with a Hertzian-wave receiver of an electrical circuit through said receiver, a relay-circuit actuated by the circuit through the receiver, a signal-circuit actuated by the relay-circuit, and means to give differing signals in said signal-circuit whereby the differing signals will be cut in or out of the signal-circuit upon the reception of a Hertzian-wave impulse.

9. The combination with a Hertzian-wave receiver of an electrical circuit through said receiver, a relay-circuit actuated by the cir-

cuit through the receiver, a signal-circuit, variable signal-lights in the same signal-circuit, and a signal-bell in the relay-circuit.

10. The combination with plural Hertzian-wave receivers of a receiving-circuit through each of said receivers, relay-circuits actuated, respectively, by the corresponding receiving-circuit, a signal actuated by each of said relay-circuits, and screens to electrically segregate each of said receivers.

11. The combination with plural Hertzian-wave receivers of an electrical circuit through each of said receivers, relay-circuits actuated, respectively, by the corresponding receiving-circuits, a signal-circuit, a danger-signal in the signal-circuit actuated by each of the relay-circuits, and metal screens to electrically segregate and shield each of said receivers.

12. The combination with plural Hertzian-wave receivers of an electrical circuit through each of said receivers, relay-circuits actuated, respectively, by the receiving-circuits, a signal-circuit, variable danger-signals in the signal-circuit actuated by each of said relay-circuits, and screens to electrically segregate and shield each of said receivers.

13. The combination with a transmitter constructed to transmit Hertzian waves simultaneously in plural directions, of plural Hertzian-wave receivers, an electrical circuit through each of said receivers, a relay-circuit actuated by the circuit through the receiver, a signal-circuit actuated by the relay-circuit, and means to electrically segregate said receivers from said transmitter.

14. The combination with a Hertzian-wave receiver, of an electrical circuit through said receiver, a tapping device to vibrate said receiver, and means to increase the time constant of the tapping device.

15. The combination with a Hertzian-wave receiver, of an electrical circuit through said receiver, a relay-circuit actuated by the circuit through the receiver, a tapping device to vibrate the receiver, and a hollow solenoid actuated by the relay-circuit to retard the action of the tapping device.

16. The combination with plural Hertzian-wave receivers arranged to simultaneously receive electric impulses from different directions, of a signal to make the direction of said impulses known.

17. The combination with plural Hertzian-wave receivers arranged to simultaneously receive electric impulses independently the one of the other from different directions, and a signal whereby each receiver may make its impulses known.

18. The combination with plural Hertzian-wave receivers arranged to simultaneously receive electrical impulses independently the one from the other from different directions, and a variable signal whereby each receiver may make its impulses known.

19. The combination with plural Hertzian-

wave receivers arranged to simultaneously receive electric impulses independently the one of the other from different directions, and independent signals whereby each receiver may make its impulses known.

20. The combination with plural Hertzian-wave receivers arranged to simultaneously receive electrical impulses independently one from the other in different directions, means to segregate the impulses received from different directions, and a signal whereby each receiver may make its impulses known.

21. In combination apparatus for simultaneously transmitting and receiving electric impulses or Hertzian waves simultaneously from different directions, and means for segregating the impulses received from different directions at the same location or station.

22. In combination apparatus for simultaneously transmitting and receiving electric impulses or Hertzian waves simultaneously from different directions, means for segregating the impulses received from different directions at the same location or station, and signals to make the direction of the segregated impulses known.

23. The combination with plural Hertzian-wave receivers arranged to simultaneously receive electric impulses from different directions, of a signal-circuit actuated by both of said receivers, and differing signals in the signal-circuit to make the direction of said impulses known.

24. The combination with plural Hertzian-wave receivers arranged to simultaneously receive electric impulses from different directions, plural relay-circuits actuated by said receivers respectively, a signal-circuit actuated by each of the relay-circuits, and differing signals in the signal-circuit to make the direction of said impulses known.

25. The combination of plural Hertzian-wave receivers arranged to receive electric impulses independently from different directions, plural relay-circuits actuated by the receivers respectively, a common signal-circuit actuated by each of the relay-circuits, differing signals in the signal-circuit to make the direction of said impulses known, a transmitter, a support for the receivers and transmitter, and means to segregate the impulses of the transmitter from the receivers.

26. The combination with plural Hertzian-wave receivers arranged to receive electric impulses independently the one from the other from different directions, relay-circuits actuated by the receivers respectively, retarding-circuits actuated by said relay-circuits respectively, tapping-circuits actuated by the retarding-circuits respectively, a common signal-circuit actuated by each of the relay-circuits, and differing signals in the signal-circuit to make the directions of said impulses known.

27. In combination apparatus for transmitting Hertzian waves in different directions,

apparatus for simultaneously receiving plural Hertzian waves from different directions, and means to segregate the receivers from the impulses of the transmitter, the transmitting apparatus and the receiving apparatus arranged to act simultaneously if desired.

28. The combination with plural Hertzian-wave receivers adapted for railroad danger-signaling without ground connections, of a signal-circuit actuated by each of said receivers, and means in the signal-circuit whereby a clear track in any given direction is indicated.

29. The combination with plural Hertzian-wave receivers adapted for railroad danger-signaling without utilizing the track as a ground or part of the circuit, of a signal-circuit actuated by each of said receivers, and means in the signal-circuit whereby a clear track in any given direction is indicated.

30. The combination with plural Hertzian-wave receivers adapted for railroad danger-signaling without ground connections, of a signal-circuit actuated by each of said receivers, and means in the signal-circuit whereby danger-signals may be received from either front or rear, and whereby the direction of the danger may be indicated.

31. The combination with plural receivers for electrical impulses or Hertzian waves adapted for railroad danger-signaling without ground connections, of a signal-circuit actuated by each of said receivers, a "clear" signal and a "danger-signal" in said signal-circuit, and means for cutting out the clear signal and cutting in the danger-signal when an electrical impulse is received by the corresponding receiver.

32. The combination with a Hertzian-wave-receiving apparatus adapted for railroad danger-signaling without ground connections, of an annunciator, said annunciator provided with means to simultaneously indicate a normally clear track in front and rear when no Hertzian-wave impulse is received, and with means to indicate the direction of danger when a Hertzian-wave impulse is received.

33. The combination with a Hertzian-wave-receiving apparatus adapted for railroad danger-signaling without ground connections, of an annunciator provided with a safety-signal to indicate a normally clear track when no Hertzian-wave impulse is received and with a danger-signal to indicate danger when a Hertzian-wave impulse is received, means to cut out the safety-signal and to cut in the danger-signal when a Hertzian-wave impulse is received.

34. The combination with a Hertzian-wave-receiving apparatus adapted for railroad danger-signaling without ground connections, of an annunciator, said annunciator provided with means to simultaneously indicate a normally clear track in front and rear when no Hertzian-wave impulse is received, and with

means to indicate the direction of danger when Hertzian-wave impulses are simultaneously received from the front and rear.

35. The combination with a Hertzian-wave transmitter of circuit-breaking mechanism in electrical circuit with the primary of the transmitter adapted to give varying signals, and a signal whereby the action of the circuit-breaker may be known.

36. In a wireless receiving and transmitting apparatus a Hertzian-wave transmitter, means whereby the transmitter will automatically give varying signals, means to denote the operation of the transmitter, a plurality of Hertzian-wave-receiving mechanisms, means to protect the receiving mechanisms from the influence of the transmitter, means to retard the action of the receiving mechanisms, a safety device for indicating that no Hertzian-wave impulses are being received, a danger device whereby the actuation of any of said receivers is indicated, means to cut out the safety device and to cut in the danger device on the reception by any receiver of a Hertzian-wave impulse, said apparatus constructed to indicate the direction from which such an impulse is received without ground connections, and a danger-signaling apparatus adapted to simultaneously send and receive Hertzian-wave impulses from any direction.

37. A danger-signaling apparatus adapted to simultaneously send and to receive Hertzian-wave impulses from different directions, and to indicate the direction from which a given impulse is received.

38. The combination with a Hertzian-wave receiver comprising an electrical circuit through said receiver, of a relay-circuit actuated by the circuit through the receiver, a retarding-circuit actuated by the relay-circuit, a tapping-circuit actuated by the retarding-circuit, and a tapping device in the tapping-circuit to vibrate the receiver, said retarding-circuit arranged to retard the action of the receiving-circuit, and the action of the tapping device.

39. The combination with Hertzian-wave receivers without ground connections, of electrical circuits through each receiver, a signal-circuit, electric magnets in said signal-circuit, variable signals operated by the signal-circuit, and means actuated by each of said magnets to cut out and to cut in either of said signals.

40. In combination a transmitter for transmitting electric impulses or Hertzian waves, a plurality of Hertzian-wave receivers arranged to simultaneously receive electrical impulses from different directions, and means to electrically segregate said transmitter and receivers at the same location or station, said receivers and transmitter arranged to act simultaneously.

41. In combination a transmitter for transmitting Hertzian waves simultaneously in dif-

ferent directions, a plurality of receivers arranged to simultaneously receive Hertzian waves from different directions, means to electrically segregate said transmitter from said 5 receivers and to segregate said receivers one from another, whereby electrical impulses may be simultaneously transmitted in different directions, and simultaneously received from different directions at the same location or 10 station.

42. A wireless receiving and transmitting apparatus comprising means for simultaneously transmitting signals by Hertzian waves in different directions, means for simultaneously receiving signals by Hertzian waves from different directions, and means whereby the direction from which a signal is received 15 may be indicated.

43. A wireless receiving and transmitting apparatus comprising means for simultaneously transmitting signals by Hertzian waves in different directions, means for simultaneously receiving signals by Hertzian waves from different directions, and means whereby 25 the direction from which a signal is received may be indicated, the transmitting apparatus and the receiving apparatus arranged to simultaneously transmit and receive signals at the same station.

30 44. A wireless receiving and transmitting apparatus comprising means for simultaneously transmitting a plurality of signals by

Hertzian waves in different directions, means for simultaneously receiving a plurality of signals by Hertzian waves from different directions, means to segregate said impulses from different directions, and means to indicate the direction from which any electric impulse is received, said transmitting and receiving apparatus arranged to simultaneously 35 transmit and receive signals from different directions.

45. The combination with plural Hertzian-wave receivers, of a receiving-circuit through each of said receivers, relay-circuits actuated, 40 respectively, by the corresponding receiving-circuit, a signal actuated by each of said relay-circuits and means to electrically segregate each of said receivers, the one from the other. 50

46. The combination with plural Hertzian-wave receivers arranged to simultaneously receive electric impulses from different directions, of a common signal-circuit actuated by either or both of said receivers, and differing 55 signals in the signal-circuit to make the direction of said impulses known.

In testimony whereof I have signed this specification in the presence of two subscribing witnesses.

FRANCIS J. GREEN.
